BEVERAGE CASE

Arthur W. Reed, Little Rock, Ark.

Application August 12, 1947, Serial No. 768,155

4 Claims. (Cl. 220—21)

1.

This invention relates to improvements in beverage cases.

An object of the invention is to provide an improved beverage case of plastic or metal which will include several inter-locking fabricated portions and spacing tubes disposable between said portions, said portions and tubes being held in assembled position in any desired manner.

Another object of the invention is to provide an improved form of beverage case including a side wall portion having inwardly rolled upper and lower edges, a fabricated top having a rolled peripheral edge supported in the upper rolled edge of said side wall portion, a corrugated bottom having a rolled peripheral edge, and a fabricated tray also having a rolled peripheral edge which is supported together with the peripheral edge on said bottom within the lower rolled edge of said side wall portion.

A further object of the invention is to provide an improved stackable beverage case formed of plastic or metal, the same being held in assembled position by means of spot welds or in any other desired manner without the use of securing rivets or bolts.

A still further object of the invention is to provide an improved stackable beverage case which will be formed without the use of rivets or bolts, and which will be prefabricated so that the same may be readily and quickly assembled.

Another object of the invention is to provide an improved plastic or metal bottle container or beverage receptacle which will be highly efficient in use, and relatively inexpensive to manufacture and produce.

Other objects will appear as the description proceeds.

In the accompanying drawings which form a part of this application,

Figure 1 is a perspective view of the improved plastic or metal beverage receptacle;

Figure 2 is an enlarged perspective view of a corner of the plastic or metal beverage receptacle or case showing the same partly broken away and in section;

Figure 3 is an enlarged perspective view of a corner of a modified form of plastic or metal beverage receptacle showing the use of spot welding for securing the receptacle in assembled position;

Figure 4 is a sectional view through a side of the modified form of beverage receptacle shown in Figure 3;

Figure 5 is a sectional view taken on the line 5—5 of Figure 1; and

2.

Figure 6 is a perspective view of a corner of a plastic or metal beverage receptacle formed with a top tray and a combined bottom tray with integrally formed side walls with the peripheral edge of the top tray being formed with a rolled bead supported in an enveloping rolled bead formed about the upper edge of said sides.

Like characters of reference are used throughout the following specification and the accompanying drawings to designate corresponding parts.

In carrying out the invention, there is provided an improved form of plastic or metal bottle container or beverage receptacle generally designated by the reference numeral 1.

The improved receptacle 1 will be prefabricated and will be readily and quickly assembled without either the use of bolts or rivets.

A substantially rectangular side wall portion 2 is provided with rounded corners 3 and is formed on its upper peripheral edge with an inwardly rolled bead 4, and is formed on its lower peripheral edge with the larger inwardly rolled bead 5. The upper portion of the side wall 2 will lie in a vertical plane, while the lower portion of said side wall 2 will be angled inwardly and downwardly, as clearly shown in the drawings.

A transversely extending top or tray 6 will be prefabricated and will be formed with a peripheral upwardly and inwardly rolled bead 7 about its edges for being received and interlocked within the bead 4 about the top of the side wall portion 2 of the beverage case 1. Transversely and longitudinally extending rows of bottle receiving openings 8 are stamped or otherwise formed through the top or tray 6 and are provided with the downwardly extending peripheral flanges 9 about each of said openings 8.

As seen best in Figures 3 and 4, an intermediate tray 10 is formed with a depending peripheral flange 11 which terminates on its lower end with the inwardly rolled bead 12 adapted to lie within the larger inwardly rolled bead 5 about the lower edge of the side wall portion 2 of the case 1. Similar transversely and longitudinally extending rows of bottle receiving openings 13 are formed through the tray 10 below and in vertical alignment with the openings 8 in the top or tray 6, and similar downwardly extending peripheral flanges 14 are formed about each of said openings 13.

Two or more openings 15 are formed through the tray 10 and are formed with the surrounding upwardly extending sleeves 16 for supporting the

tubular or cylindrical spacing tubes 17 extending between the top tray 6 and the intermediate tray 10.

A bottom 18 is provided with spaced transverse upwardly extending corrugations 19 for receiving the tops of the rows of bottles (not shown) in a lower case when said cases are stacked one upon another, and for supporting the rows of bottles in the case 1 in which the bottom 18 is supported. The bottom 18 is formed with a depending peripheral side wall 20 which is angled inwardly to extend in parallel relation to the lower part of the side wall portion 2 of the case 1, and is formed with an inturned peripheral bead 21 received within the bead 12 on the intermediate tray 10.

The space from the lower surface of the bottom 18 to the lower portion of the larger rolled bead 5 on the side wall portion 2 will provide sufficient support for keeping the same stacked firmly when being washed and rinsed.

From the foregoing description, it will be seen that the hereinbefore described beverage case will be held in assembled position without the use of rivets or bolts of any type.

The form of the invention illustrated in Figures 1, 2 and 5 contemplate the use of a case 22 having a side wall portion 23 which is angled inwardly as at 26 adjacent its lower edge and formed with an integral solid bottom 25.

The upper peripheral edge of the side wall portion 23 is rolled inwardly as at 26.

Upper and lower bottle supporting trays 27 and 28 respectively are provided with upwardly extending attaching flanges 29 and 30 respectively and are attached to the inner surface of the side wall portion 23 by means of the spot welds 31.

Vertically aligned rows of openings 32 and 33 are formed through the trays 27 and 28 and are surrounded by the depending peripheral flanges 34 and 35 respectively.

Supporting collars 36 are formed upon the lower tray 28 and support the cylindrical spacing tubes 37.

Hand hold openings 38 and 39 will be formed in the ends and sides of the side wall portion 23 and have their upper and lower edges rolled as at 40 and 41 respectively to prevent cutting or injury of the hands when handling the cases.

In Figure 6 of the drawings there is shown an improved plastic or metal beverage case comprising a transversely extending top or tray 42 formed with a peripheral upwardly and inwardly rolled bead 43. A combined bottom or tray 44 will be formed with integral side and end walls 45 and 46 respectively and the upper edges of said side and end walls 45 and 46 will be formed with the inwardly and downwardly rolled, locking beads 47 which will surround the beads 43, on the top or tray 42 to firmly interlock and support the same.

Transversely and longitudinally extending rows of bottle receiving openings 48 will be formed through the top or tray 42 and will be formed with downwardly extending peripheral flanges 49 about each of said openings 48.

Transversely and longitudinally extending rows of circular depressed seats or wells 50 will be formed in the bottom or tray 44 directly under and in vertical alignment with the openings 48 for receiving and supporting beverage bottles (not shown).

The upper surface of the bottom or tray 44 will be slightly elevated about the bottoms of the seats or wells 50.

As in the other forms of the invention tubular or cylindrical spacing tubes 51 will be disposed between the top or tray 43 and the bottom or tray 44 for adding strength and rigidity to the completed beverage case.

From the foregoing description it will be seen that there has been devised and provided a highly efficient form of beverage container which will be prefabricated and assembled readily without the use of rivets or bolts of any type and which may be manufactured at a relatively inexpensive cost.

While the preferred embodiment of the instant invention has been illustrated and described it will be understood that it is not intended to limit the scope of the invention thereto as many minor changes in detail of construction may be resorted to without departure from the spirit of the invention.

Having described the invention, what is claimed as new is:

1. A beverage case comprising prefabricated side and end walls formed with inwardly extending upper and lower rolled edges, a bottom therefor formed with spaced and transversely extending raised corrugations, the under side of said corrugations providing bottle top receiving recesses whereby when a plurality of cases are vertically stacked the bottle tops of a lower case 20 will be firmly held in the recesses, a peripheral rolled edge on said bottom supported in the lower rolled edge on said side and end walls, top and intermediate trays having vertically aligned rows of bottle supporting openings alignable with 25 said spaced corrugations and formed with peripheral rolled edges respectively supported in the rolled edges in the top and bottom of said case side and end walls, the lower portions of said case side and end walls tapering downwardly and inwardly whereby a plurality of cases 30 may be vertically stacked, and spaced reinforcing means disposed between said trays and secured thereto at their opposite ends.

2. A beverage case comprising prefabricated side 45 and end walls formed with inwardly extending upper and lower rolled edges of different sizes, a bottom therefor formed with spaced and transversely extending raised corrugations, the under side of said corrugations providing bottle top receiving recesses whereby when a plurality of cases 50 are vertically stacked the bottle tops of a lower case will be firmly held in the recesses, a peripheral rolled edge on said bottom supported in the lower rolled edge of said side and end walls, top and intermediate trays having vertically aligned rows 55 of bottle supporting openings alignable with said spaced corrugations and having depending peripheral flanges formed about said openings, said trays having peripheral rolled edges respectively supported in the rolled edges in the top and bottom of said case side and end walls, the lower portion of said case side and end walls tapering downwardly and inwardly whereby a plurality of cases 60 may be vertically stacked, spaced collars 65 formed on the upper surface of the lower tray, and cylindrical reinforcing and spacing tubes disposed about said collars extending between said trays and secured thereto at their opposite ends.

3. A beverage case comprising prefabricated side and end walls formed with inwardly extending upper and lower rolled edges, a bottom therefor formed with spaced and transversely extending raised corrugations, the under side of said 75 corrugations providing bottle top receiving re-

cesses whereby when a plurality of cases are vertically stacked the bottle tops of a lower case will be firmly held in the recesses, a peripheral rolled edge on said bottom supported in the lower rolled edge on said side and end walls, top and intermediate trays having vertically aligned rows of bottle supporting openings alignable with spaced corrugations and formed with peripheral rolled edges respectively supported in the rolled edges in the top and bottom of said case side and end walls, and the lower portion of said side and end walls tapering downwardly and inwardly whereby a plurality of cases may be vertically stacked.

4. A beverage case comprising prefabricated side and end walls formed with inwardly extending upper and lower arcuately rolled edges, a bottom therefor formed with spaced transversely extending raised corrugations and having a peripheral rolled edge receivable for locking engagement in the lower rolled edge on said side and end walls, top and intermediate trays having vertically aligned rows of bottle supporting openings formed with peripheral rolled edges respectively receivable in the rolled edges on the top and bottom of said case side and end walls whereby the trays may be locked in supported position.

ARTHUR W. REED.
